UNITED STATES PATENT OFFICE.

CLIFTON P. RUGGLES, OF OSAWATOMIE, KANSAS.

SIGNAL.

No. 853,737.

Specification of Letters Patent.

Patented May 14, 1907.

Application filed November 28, 1906. Serial No. 345,441.

To all whom it may concern:

Be it known that I, CLIFTON P. RUGGLES, a citizen of the United States, and a resident of Osawatomie, in the county of Miami and State of Kansas, have invented a new and Improved Signal, of which the following is a full, clear, and exact description.

This invention relates to signals, and especially to signal flags.

10 The invention constitutes an improvement of the invention described in an application for signal which was allowed to me June 7, 1906, Serial No. 286,004.

15 The object of the invention is to produce a signal carrying several flags, any of which may be quickly brought into view when desired; a further object being to construct the parts so as to enable the signal flags to be readily removed when it is desired to use the 20 same as an ordinary signal.

The invention consists in the construction and combination of parts to be more fully described hereinafter and particularly set forth in the claims.

25 Reference is to be had to the accompanying drawings forming a part of this specification, in which similar characters of reference indicate corresponding parts in all the figures.

30 Figure 1 is a front elevation of a signal constructed according to my invention, a portion of the body thereof being represented as broken away; the lower portion of the device is also broken away; Fig. 2 is a longitudinal vertical section through the device, a portion thereof being broken away, as in Fig. 1; Fig. 3 is a horizontal cross section taken on the line 3—3 of Fig. 2, certain parts being represented broken away; Fig. 4 is a cross 35 section on the line 4—4 of Fig. 2; and Fig. 5 is a cross section on the line 5—5 of Fig. 2.

Referring more particularly to the parts, 1 represents the inner case of the device, which consists of a tubular sheath the lower extremity whereof receives a head 2, the upper portion of said head being formed into a cup 3 which is received in the interior of the case as shown most clearly in Fig. 2. Upon the upper portion of the inner case 1, there is received an outer case 4, which telescopes over the same as indicated very clearly in Fig. 2. The upper portion of this outer case 4 is formed into a cap or hood 5 so that the interior of the case is protected above. At one side, the inner case 1 is provided with an elongated rectangular opening 6, for a pur-

pose which will appear more fully hereinafter. A similar opening 7 is provided in the outer case, and these openings are adapted to be brought into alinement by rotating the outer 60 case so as to enable the flags within the case to be brought into view.

I provide means for locking the outer case upon the inner case in several positions, for which purpose the outer case is provided with an inward offset or button 8 which is formed by pressing the material inwardly as indicated in Fig. 4, and this button is adapted to engage with any one of three openings 9, 10 and 11. When in engagement with the 70 opening 9, as shown in Fig. 4, the openings 6 and 7 are not in alinement, from which arrangement the interior of the case is completely inclosed. When the button 8 is in engagement with the opening 11, the opening 75 7 will be in alinement with the opening 6, so as to permit any of the flags to be exposed, and when the button engages the opening 10, the edges of the openings 6 and 7 are adapted to overlap slightly so as to catch a flag which 80 may be extended therethrough in such a way as to hold the same against being returned. The purpose of this arrangement will be described more fully hereinafter.

It will be understood that the inner and 85 outer cases are formed of sheet metal which has a certain amount of resiliency, permitting the button 8 to be readily disengaged from any of the openings 9, 10 and 11 with which it may become alined.

90 In the upper portion of the inner case, a disk or plug 12 is received, and at the center of this plug there is attached a spindle 13 which is connected with the same by means of screw threads, as shown; the lower extremity of the said spindle being seated in a socket or bore 14 in the upper side of the head 2 as indicated most clearly in Fig. 2. The extremity of the spindle 13 projects above the plug 12 and receives a nut 15. 100 This nut screws down upon and retains in position a rotatable collar 16, which is pressed up against the face of the nut by a small helical spring 17, as indicated in Fig. 2, the said spring being seated upon the upper face of 105 the plug. This collar 16 is of substantially circular form, but is formed with an arcuate elongated notch or recess 18 at one edge thereof, for a purpose which will appear hereinafter.

110 The disk or plug 12 is provided with three openings 19^a with radially extending slots 19

- which open upon the edge of the plug as shown. In the interior of the inner case three flag staffs 20 are provided, and these staffs have elongated wooden bodies 21 provided with longitudinally extending wire cleats 22 which facilitate the attachment of flags thereto. The ends of the sticks receive loose caps 24 having reduced necks 23 which are dropped into the openings 19^a to retain 10 the upper ends of the sticks, as in Fig. 3. The caps are formed with collars 24^a, the lower faces of the said collars resting upon the upper face of the plug.
- The lower extremities of the sticks 21 are 15 provided with sockets 25, and from the lower portion of these sockets 25 stems 26 extend downwardly. The lower extremities of these stems 26 are received in sockets 27 formed in the upper face of the head 2 as shown, and 20 adjacent to these sockets the stems are provided with ratchet wheels 28, the teeth of which project in an inclined direction, as indicated in Fig. 5. Loosely mounted on the stems 26, near the ratchet wheels, I provide 25 shoes 29, the form of which is very clearly shown in Fig. 4; they present circumferentially disposed outer edges which are adapted to lie against the inner face of the case, and have substantially straight inner edges 30 as shown. To these shoes 29 helical springs 30 are attached, the said springs being arranged around the stems 26 as shown. The upper extremities of the springs are fixed to the sockets 25.
- 35 Around the lower portion of the head 2, outwardly projecting brackets 31 are provided, and these brackets are disposed in radial alinement with the stems 26. The outer extremities of the brackets operate as guides 40 for plungers 32 which extend inwardly through the wall of the cup 3, so that the inner ends of the plungers engage with the teeth of the ratchet wheels 28. Against the outer portions of the brackets 31, helical springs 33 45 thrust, and the inner extremities of these springs thrust against pins 34 mounted transversely in the plungers. From this arrangement it will be understood that the springs 33 tend to hold the plungers in engagement 50 with the ratchet wheels, but by pulling outwardly upon the head 35 of any one of the plungers, the corresponding ratchet wheel may be disengaged therefrom. The flags, such as the flag illustrated at 36 in Fig. 4, are 55 normally held wrapped upon the sticks. The flags will be of different colors or have different significance when exposed. It should be understood that when the openings 6 and 7 are in alinement, any flag may be drawn outwardly so as to expose its body at the side of the outer case. When it is drawn out in this manner, it will be understood that the stem 26 which corresponds to this flag will rotate 60 the corresponding ratchet wheel, so that the 65 spring about the stem will become wound up.

The spring will be evidently held against unwinding by the corresponding plunger, but upon pulling the plunger outwardly, the spring will operate to wind the flag again upon its stick. In case the plungers or ratchet 7c wheels should get out of order, any one of the flags may be locked in its exposed position by pinching the same between the edges of the openings 6 and 7. In order to do this, it is only necessary to rotate the outer case 75 until the button 8 engages with the opening 10, in the manner suggested above.

The head 2 is provided at one side with a lug 37, which projects outwardly as indicated, and this lug is provided with a longitudinal bore receiving a shank 38 formed on a latch 39 of wire or similar material. The body of this latch extends upwardly in an inclined position, and is formed with an inwardly projecting finger 40; this finger normally projects through any one of three openings 41 which are formed in the outer case near the lower portion thereof, the inner extremity of the finger being received in a recess 42 which is formed in the outer wall of 90 the cup. These openings 41 are so arranged that when a certain opening is opposite the recess, a certain flag will be in position to be extended from the case. In practice, the outer side of the case will be marked at the 95 proper point so as to indicate whether the flag to be drawn out will be red or green, etc.

It should be understood that the latch 39 is of resilient material so that it may be 100 readily pulled outwardly so as to disengage the finger 40 from the recess and the opening so as to enable the inner case to be rotated. Normally, of course, the latch locks the inner case to the head and prevents the rotation or removal of the inner case from 105 the head. When the collar 16 has the position shown in Fig. 3, its outer edge overlaps the edges of all the heads 24, so that it locks the flag staffs in position. When it is desired to remove one of the flag staffs for hand 110 signaling, it is only necessary to remove the outer and inner casing, whereupon the caps 24 may be raised and the staffs disengaged from the slots, the stems 26 being, at the same time, pulled out of the sockets 27 in 115 which they seat. The flag may then be used as an ordinary signal.

The lower side of the head 2 is formed with an downwardly projecting pintle 43 which is adapted to be received in a socket to hold the signal in an erect position. In order to facilitate the attachment of the flags to the sticks, at suitable points the sticks are provided with recesses or notches 44 under the cleats and through which a portion of the 12c flag may be drawn.

While the signal is intended to be used especially by railroads, it will be also very useful in other situations where a plurality of different signals must be shown from time to 130

time; thus, it could be used very advantageously by the Weather Bureau for indicating the prophesied changes in the weather.

Having thus described my invention, I claim as new and desire to secure by Letters Patent:

1. In a signal, in combination, a tubular case, a removable head received in the lower end thereof, a spindle attached in said head and extending upwardly in the interior of said case, a plug carried by the upper end of said spindle and flag staffs removably mounted in said head and said plug, said case having an opening through which flags rolled on said staffs may be extended.

2. In a signal, in combination, a tubular inner case, a head removably mounted in the lower end thereof, a spindle attached in said head, a plug carried by said spindle and held in the upper portion of said case, flag staffs removably attached in said plug and said head, a tubular outer case covering said inner case and protecting the upper end thereof, said cases having openings adapted to aline to enable flags on said staffs to be extended therethrough.

3. In a signal, in combination, a tubular inner case, a head removably mounted in the lower end thereof, a spindle attached in said head, a plug carried by said spindle and held in the upper portion of said case, flag staffs removably attached in said plug and said head, a tubular outer case covering said inner case and protecting the upper end thereof, said cases having openings adapted to aline to enable flags on said staffs to be extended

therethrough, said outer case having means for locking the same with the opening of said outer case in different positions.

4. In a signal, in combination, an inner case, a head removably mounted in the lower end thereof, a spindle attached in said head and extending upwardly in said inner case, a plug attached to said spindle and having openings formed with slots extending to the edge of said plug, flag staffs having their lower ends mounted in said head, heads slidably received on the upper ends of said staffs and adapted to drop into said openings to hold said staffs in said plug.

5. In a signal, in combination, an inner case, a head removably mounted in the lower end thereof, a spindle attached in said head and extending upwardly in said inner case, a plug attached to said spindle and having openings formed with slots extending to the edge of said plug, flag staffs having their lower ends mounted in said head, heads slidably received on the upper ends of said staffs and adapted to drop into said openings to hold said staffs in said plug, said spindle projecting above said plug, and a collar carried by said spindle above said plug and adapted to lock said collars against rising from said openings.

In testimony whereof I have signed my name to this specification in the presence of two subscribing witnesses.

CLIFTON P. RUGGLES.
